United States Patent Office

Des. 227,382

Patented June 19, 1973

227,382

PLAYGROUND SPIRAL SLIDE

Robert S. Wormser and Ronald L. Ewers, Hillsdale,
Mich., assignors to Game Time, Inc., Litchfield, Mich.

Filed Feb. 14, 1972, Ser. No. 226,359

Term of patent 14 years

Int. Cl. D21—03

U.S. Cl. D34—5 E

FIG. 1

FIG. 2

FIG. 3

FIG. 1 is an elevational, perspective view of our new design for a playground spiral slide as taken from the right and front thereof.

FIG. 2 is an elevational, perspective view taken from the rear, and

FIG. 3 is a top plan view of our new design.

We claim:

The ornamental design for a playground spiral slide, substantially as shown and described.
